LUG STRAP SUPPORT

Wingo Herron, Augusta, Ga.

Application March 29, 1938, Serial No. 198,754

1 Claim. (Cl. 139—154)

The invention relates to a lug strap support and more especially to a lug strap hanger and reinforcement device.

The primary object of the invention is the provision of a device of this character, wherein there is eliminated breakdowns caused by the wear and breakage of the lug strap hanger or power strap in looms and also such device can be easily and quickly regulated, reducing the wear thereon to a minimum and avoiding the use of screws or other like fasteners in the picker sticks with the result that safety is assured to the operator or attendant of the loom.

Another object of the invention is the provision of a device of this character, wherein reinforcement is assured to the lug strap or power strap of a loom and also that friction in the working of the said strap in association with a picker staff or stick is reduced to a minimum, the fasteners for the device being disposed to avoid beams of yarn being snagged as the same are trucked or hauled between looms in side aisles or alleys thereto and also avoids the fasteners for such device being engaged in the picker stick which weakens the same and also such stick will be reinforced at the point of the lug strap or power strap.

A further object of the invention is the provision of a device of this character, which is simple in its construction, easy of application without requiring the removal of the stick or staff from the loom, thoroughly reliable and efficient in operation, strong, durable, avoiding the removal of the lug strap from the picker stick on the application of the said device into operating position and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation of a picker stick of a loom showing the lug or power strap in position thereto and the device constructed in accordance with the invention applied, the latter being partly in section.

Figure 2 is an enlarged sectional view taken on the line 2—2 of Figure 1 looking in the direction of the arrows.

Figure 3 is a vertical transverse sectional view taken approximately on the line 3—3 of Figure 2 looking in the direction of the arrows.

Figure 4 is an enlarged vertical longitudinal sectional view through the device and the lug or power strap in association therewith.

Similar reference characters indicate corresponding parts throughout the several views in the drawing.

Referring to the drawing in detail, 10 designates generally a picker stick or staff of any well-known type, being generally made from straight grain hard wood and having as usual a hole 11 10 for the purpose of attaching the strap (not shown) of a parallel-motion device for a loom.

Carried about the picker stick or staff 10 is the long lug strap 12, its connection being indicated at 13 with an operative part of a loom. 15 The strap 12 is fastened to the connection 13 at 14 and as usual is looped about the picker stick or staff 10 while correlated with the said strap 12 is the strap 15 which in its width is substantially the width of the picker stick or staff 10 and is 20 adjustably disposed at the outer side thereof or the outermost longer narrow edge of the same. The looped strap 12 is accommodated in an eye or open frame unit 16 having an upstanding ear 17 at the uppermost portion thereof and this 25 ear cooperates with a clamping plate 18, these being adapted for disposition crosswise of the picker stick or staff 10 above the plane of the strap 12. Carried through suitable clearances in the ear 17 and plate 18 are headed bolts 19, these 30 being disposed at opposite sides of the picker stick or staff 10 and upon their ends next to the plate 18 are threaded the nuts 20 bearing against washers 21 and 22, respectively, about the said bolts and between the plate 18 and the said nuts 20. 35

The ear 17 straddles the strap 15 and by the nut-carrying bolts 19 this strap will be clamped in working position upon the stick or staff 10, being carried through the strap 12 in this position. The eye or frame unit 16 in that side next to the 40 stick or staff 10 is provided with a seating channel or groove 23 of a size to accommodate the said strap 15 and portion adjacent thereto of the stick or staff 10 being clearly shown in Figure 4 of the drawing.

The eye or open area 24 of this unit 16 is of a size to loosely receive the strap 12 when the latter is looped about the stick or staff 10 in a manner as shown in Figure 3 of the drawing. The sides, top and bottom edges confronting the eye or 50 opening 24 in the unit 16 are preferably rounded at 25 minimizing contacting area of the strap 12 with the unit 16 and thus decreasing friction in the operation of the picker stick or staff 10.

By the bolts 19, the unit 16 with the strap 15 55

can be conveniently regulated with relation to the stick or staff 10 and these bolts have their heads 26 outermost of the stick or staff 10 while the nuts 20 are innermost toward the loom and in this way snagging of yarn during haulage thereof in the aisles or alleys between the looms using the device will be entirely avoided or eliminated.

What is claimed is:

- 10 10. A lug strap support comprising a frame having an open center forming an eye for receiving

a lug strap and also provided with an inset picker stick seat in one side thereof for accommodating a picker stick, an ear at the uppermost portion of the frame, means engaged in said ear and embracing the picker stick for holding the frame 5 thereon and accommodating the lug strap within the eye when about said picker stick, and a strap engaged by said means and depending within the seat for the picker stick for disposition between it and the said frame.

WINGO HERRON.
